UNITED STATES PATENT OFFICE.

DOCTOR FRANKLIN OLIVER, OF OAKLAND, CALIFORNIA; LILLIE F. OLIVER EXECUTRIX
OF D. FRANKLIN OLIVER, DECEASED.

VEHICLE-BODY.

1,286,741.

Specification of Letters Patent.

Patented Dec. 3, 1918.

Application filed August 7, 1915, Serial No. 44,271. Renewed April 23, 1918. Serial No. 230,378.

To all whom it may concern:

Be it known that I, DOCTOR F. OLIVER, a citizen of the United States, residing at Oakland, in the county of Alameda and State of California, have invented certain new and useful Improvements in Vehicle-Bodies, of which the following is a specification.

This invention relates to certain new and useful improvements in a vehicle body, and appertains more particularly to the construction of bodies for automobiles.

The primary object of the invention resides in the provision of a compact, yet roomy and comfortable type of automobile body. Further, the invention resides in mounting a window sash for a side door whereby it may be moved adjacent the wind shield to provide an extension for the latter. Another object of the invention is to provide ample space for the occupants and storage purposes.

The invention further resides in the features of construction hereinafter described and claimed and which are depicted in the preferred embodiment in the accompanying drawings wherein;

Figure 1 is a fragmentary side elevation of a vehicle body embodying the invention, portions being broken away;

Fig. 2 is a partial top plan of a portion of the car showing the sash in dotted lines when employed as a wind shield;

Fig. 3 is a horizontal section through the door taken on line 3—3 of Fig. 1;

Fig. 4 is a vertical section of the door;

Fig. 5 depicts the manner of fastening the sash to the main wind shield when the former is used as a shield extension;

Fig. 6 is a horizontal section on line 6—6 of Fig. 5;

Fig. 7 is a perspective of the window sash support; and

Fig. 8 is a similar view of the sash forward locking member.

Using similar characters to designate like parts, the numeral 1 refers to the body in general, 2 the wind shield, 3 the top and 4 the floor which has its side cut-out to provide sufficient room for a step 5, the latter being included within the body lines.

The side of the body or car is provided with a door-way 6 extending down to the step and which is closed by the door 7 hingedly mounted at 8 to swing open forwardly.

This door is preferably formed of metal secured to a wooden frame 9 for forming a chamber 10 into which the sash 11 may be lowered. The sash support consists of a sill 12 and a vertical standard 13 to which latter the sash is mounted by hinges 14. As shown in Fig. 3, one wing of each hinge 14 is secured to the forward edge of the standard and the other wing overlaps the standard and is secured to the sash 11 whereby the vertical axis of the pivot of said hinge is in proximity to that of hinges 8 for the reason hereinafter made apparent.

The forward edge of the standard 13 is grooved, as at 15, and the opposite edge of the sill is similar grooved, as at 16, to aline with a groove 17 on the free edge of the sash. The opposite end walls of sash chamber 10 are formed with vertical ribs 18 for normally engaging in grooves 15 and 16 of the sash support and adapted to enter groove 17 of the sash to guide the latter and its support during the vertical sliding movement into and out of the sash chamber.

The top of the sash carries a flange 19 to serve as a closure for the chamber 10 when the sash is therein.

When the sash is elevated from the chamber, the support is retained in the position illustrated in Fig. 1 and in dotted lines in Fig. 4, by a bolt or pin 20, which is threaded throughout the door back 9, engaging in a provided recess 21 of the sill.

The sash is locked to its sill by a slidable bolt 22 entering the keeper 23 formed in the sill.

When it is desired to use the sash as a rearward extension to the main wind shield 2, the sash is unlocked from its sill and swung forwardly on its hinges to have its free edge disposed rearwardly of and in proximity to the aforesaid shield 2. A latch bolt 24 has a rearward bifurcated extension 25 adapted to slidably engage with a stud 26 carried by the sash and thereby providing a pin and slot connection between the sash and shield. The latch 24 is also provided with a longitudinal slot 27 through which a winged screw 28 passes for adjustably securing the latch to the wind shield 2. When the door is opened the eccentricity of the hinges 8 and 14 causes the sash to move forwardly which movement is accommodated by the sliding engagement of the stud 26 in 110

the bifurcated end of latch plate 24. If sufficient space is not had for the stud, the latch 24 may be adjusted forwardly by manipulating the screw 28. It will thus be noted that the sash serves to extend the door to the top 3 of the vehicle thereby closing this space and eliminating the usual side curtains at this point. Further, greater convenience in entering the car is afforded.

On the inner side or back of the door 7 is provided a pocket 29 in which curtains may be stored and which is closed by a flap 30. This arrangement does away with the usual equipment for housing the side curtains in the top 3.

The bottom of the door is extended inwardly over the step 5 and supports a tool or other receptacle 31, the closure 32 of which lies flush with floor 4 and whereby the receptacle forms a filler to supplement the floor cut out in forming a regular and even floor extending the full width of the body.

By this provision, it is possible to have a mat 33 constantly on the step as the door and its receptacle 31 overlies the same to keep it dry and in place on the step.

What is claimed is:

1. A vehicle body having a top and wind shield, a hinged entrance door, a vertically movable support carried entirely by the door for movement therewith, and a sash movably mounted on the support for movement independent of the position of the door for being disposed in a position in proximity to the wind shield to constitute an extension of the latter.

2. A vehicle body having a top and wind shield, an entrance door spaced rearwardly from the shield, a vertically movable support carried entirely on the door for movement therewith, a sash movably carried by the support for movement forwardly in proximity to the wind shield to form an extension thereof, and means for holding the support in its upper position and the sash in its forward position.

3. A vehicle body having a top and wind shield, an entrance door spaced rearwardly from the shield, a vertically movable support carried entirely on the door for movement therewith and a sash hinged to the support for closing the space between the door and top.

4. A vehicle body having an entrance

opening, a hinged door therefor, a wind shield spaced forwardly from the door, and a sash pivotally carried by the door for normally closing the space above the door and adapted for swinging forwardly adjacent the wind shield to form a rearward extension thereof.

5. A vehicle body having an entrance opening, a door for the body opening provided with a chamber, a wind shield on the body, a sash support slidable vertically in the door chamber and carried for swinging with the door, a sash hinged to the support for swinging forwardly in proximity to the wind shield to form a rearward extension thereof, and a detachable connection slidably joining the sash to the wind shield, for guiding the sash when the door is operated.

6. A vehicle body having an entrance opening, a door therefor hinged to the body, a wind shield arranged on the body in advance of the door, a sash support mounted on the door for swinging therewith, a sash hinged to the support eccentrically with the door hinge for swinging in proximity to the wind shield, and a sliding connection between the latter and the sash for guiding the latter when the door is operated.

7. A vehicle body having an entrance opening, a door therefor hinged to the body, a wind shield arranged on the body in advance of the door, a sash support on the door, a sash hinged to the support for swinging in proximity to the wind shield to form an extension thereof, and a pin and slot connection between the sash and wind shield.

8. A vehicle body having an entrance opening, a door hinged for closing the body opening, a wind shield arranged in advance of the door, a sash hingedly supported by the door for swinging toward the wind shield to form an angular extension therefor, the axis of the sash hinge being vertically offset from the axis of the door hinge, and a latch connecting the sash to the shield for relative movement to permit of the door being operated.

In testimony whereof I affix my signature in the presence of two witnesses.

DOCTOR FRANKLIN OLIVER.
